UNITED STATES PATENT OFFICE

ANTHONY J. STOUGES, OF QUEENS VILLAGE, NEW YORK, ASSIGNOR TO MERGENTHALER LINOTYPE COMPANY, A CORPORATION OF NEW YORK

SLUG CASTING MACHINE

Application filed October 25, 1929. Serial No. 402,329.

This invention relates to typographical casting machines, such as linotype machines of the general organization represented in U. S. Letters Patent to O. Mergenthaler No. 436,532, wherein circulating matrices are released from a magazine in the order in which their characters are to appear in print and then composed in line, the composed line transferred to a vertically movable trans- 10 porter or first elevator which presents them to a mold, the mold filled with molten metal to form a slug or "linotype" against the matrices which produce the type characters thereon, and the matrices thereafter elevated 15 and returned through a distributing mechanism to the magazine from which they started.

In these machines, it is frequently necessary to vary the vertical position of the first 20 elevator prior to casting, in order to bring about the proper alignment of the matrix characters with the mold slot. Thus, in the use of regular two-letter matrices, whose characters range from 5½ pt. to 14 pt. in 25 height, the elevator is in most instances allowed to descend to its lowermost level; whereas, in the use of head letter matrices, whose single characters range from 14 pt. to 36 pt., the elevator is arrested at a slightly higher level. In the former case, the elevator banks directly upon the so-called "vise frame", while in the latter case, a so-called filler piece or stop member is usually employed to arrest the elevator at the higher 35 level. While composed lines of matrices of these different sizes may thus be presented to the different molds at the proper levels, it is necessary when casting from display matrices, whose characters range from 36 pt. 40 to 45 pt. and above, to arrest the elevator at a still higher or third level, and machines capable of handling these display fonts are therefore equipped with a second filler piece or stop member which may be brought into 45 action when required to effect the arrest of the first elevator at such third level.

When the two stop members are thus employed in the same machine, they are pivotally mounted upon the vise frame, and each is 50 provided with a hinged contact portion

through which the "vise automatic" is actuated in the different arrested positions of the elevator (see the Kennedy Patent No. 1,595,947). That is to say, when the elevator is arrested by either stop member, the hinged contact portion of said member is depressed by a pin in the elevator head and strips the vise automatic as the elevator comes to rest, so as to allow the machine to complete its cycle of operation. Otherwise, the vise automatic acts to disengage the main driving clutch and stop the operation of the machine. 55 60

The molds employed for casting from the three different matrix fonts mentioned differ 65 as to form and are so designed that they require the composed matrix lines to be presented thereto at three different levels. For example, if a head-letter mold happens to be the one selected, the first elevator must be 70 arrested at the second or intermediate level, as otherwise damage to the matrices or elevator at the time of the lock-up is apt to result. The same is true of the regular two-letter matrices or of the display matrices, it being 75 necessary that the stop members be properly adjusted according to the mold in use.

The present invention is intended to obviate these and other difficulties, and aims to prevent the presentation of a matrix line to the mold and the subsequent casting operation except under the proper conditions. To this end, whenever the molds and stop members are in improper relative adjustment, automatic safety devices are provided to arrest 80 the elevator in its descent at a point above the stop members so as to effect the stoppage of the machine through the medium of the vise automatic. In the preferred embodiment 85 illustrated, these safety devices include an arresting finger pivotally mounted in the first elevator and adapted, as the latter is raised and lowered, to be moved under the control of the second stop member into and out of engaging relation to fixed banking blocks associated with the different molds. The specific construction and mode of operation 90 will best be understood from the detailed description to follow.

In the accompanying drawings, the inven- 100

tion is shown merely in preferred form and by way of example, but obviously many changes and variations may be made therein, which will still be comprised within its spirit.

5 It should therefore be understood that the invention is not limited to any specific form or embodiment except insofar as such limitations are specified in the claims.

Referring to the drawings:

10 Fig. 1 is a fragmentary perspective view showing a portion of the casting mechanism of a linotype machine equipped with the present improvements, the first elevator being indicated by broken lines in the casting position;

15 Fig. 2 is an end view of the first elevator head;

20 Fig. 3 is a detail perspective view, showing the manner of mounting the supporting bracket plate for the safety device;

25 Fig. 4 is a front elevation, partly broken away, showing the level at which the elevator is arrested when the stop members are improperly adjusted for a regular mold;

30 Fig. 5 is a similar view, but showing the level at which the elevator is arrested when the stop members are properly adjusted for a regular mold;

35 Figs. 6 and 7 are views similar to Figs. 4 and 5, showing, respectively, the levels at which the elevator is arrested when the stop members occupy an improper and a proper position of adjustment for, say, a 36 pt. head-letter mold;

40 Figs. 8 and 9 are also views similar to Figs. 4 and 5, and showing respectively the levels at which the elevator is arrested when the stop members occupy an improper and a proper position of adjustment for, say, a 45 pt. display mold;

45 Fig. 10 is a front elevation, partly broken away, showing the regular stop member in a normal operative position and the elevator arrested thereby to present a line of two-letter matrices in the upper position;

50 Figs. 11, 12 and 13 are vertical sections taken respectively on the lines 11—11, 12—12 and 13—13 of Figs. 4, 6 and 8; and

55 Fig. 14 is a similar sectional view, showing the level at which a matrix line would, in the absence of the present improvements, be presented to a head-letter mold when both stop members are in their inactive position.

Linotype machines capable of handling both head-letter and display matrix fonts, in addition to the regular matrix fonts, are usually provided with three different types of molds to correspond, these molds being mounted in a rotary wheel or disc A, which is manually adjustable to bring any one of the molds into use to the exclusion of the others. The regular mold B (as best shown in Fig. 11) is formed with two aligning ribs B¹, B² adapted, by their engagement with the lower ears x of the ordinary two-letter matrices

X, to locate the lower or upper characters thereof in registry with the mold slot; whereas the larger head-letter mold C (Figs. 12 and 14) and the still larger display mold D (Fig. 13) are formed with only one aligning rib C¹ or D¹, which is adapted by its engagement with the lower ears y or z of the corresponding matrices Y or Z, to locate the single character of such matrices in registry with the mold slot. In this connection, however, it may be noted (compare Figs. 11, 12 and 13) that, while the thickness of the aligning rib C¹ of the head-letter mold C is the same as that of the corresponding rib B¹ of the regular mold B, the aligning rib D¹ of the display mold D is considerably thinner, due to the fact that the larger characters of the display matrices Z are punched with reference to a different datum line, all as more fully explained in the Kennedy Patent No. 1,306,909.

The first elevator E, which presents the composed matrix lines to the mold in use, is provided as usual with two vertical pins or set screws E¹ and E², the former acting as a stop to limit the descent of the elevator, and the latter being arranged to operate the so-called "vise automatic" G as the elevator comes to rest. In casting type lines from the two-letter matrices X of the regular fonts, the first elevator E is generally allowed to descend to its lowermost level, the stop pin E¹ at such times banking directly upon the vise frame F. Under such conditions, the matrices X (whether composed at the upper or lower level or both) will be properly presented to the mold B, the ears x being adapted to cooperate with the lower aligning rib B² or the upper aligning rib B¹ according to the level at which the matrices are composed. Under such conditions, too, the vise automatic G will be depressed by the pin E² and the machine allowed to complete its cycle of operation, the mold disc A being immediately advanced to carry the mold B against the composed line for "face alignment", and the elevator being lifted slightly to align the matrix characters horizontally with the mold slot preparatory to the casting of the slug.

In casting "solid" lines of italics from the two-letter matrices X, it is common practice to compose the matrices, not at the upper level as would otherwise be necessary, but at the lower level and then to arrest the first elevator in a raised position with reference to the mold B so as to bring about the registration and alignment of the lower (italic) characters with the mold slot. For this reason, the machine is usually equipped with a filler piece or stop member H, which (as best shown in Fig. 1) is arranged on top of the vise frame and pivotally mounted thereon so that it may be swung into and out of operative position. The stop member H is formed with an integral contact por-

tion H^1 to cooperate with the pin E^1 in arresting the first elevator in its raised position, and with a hinged contact portion H^2 to cooperate with the pin E^2 in operating 5 the vise automatic G in the arrested position of the first elevator.

Since the characters of the head-letter matrices Y are punched with reference to the same datum line as that of the lower characters 10 of the regular two-letter matrices X , the stop member H may be, and is, utilized in casting type lines from said head-letter matrices. In other words, the stop member H is also adapted, when in active position, 15 to arrest the first elevator E at the required level to locate the head-letter matrices Y in proper relation to the corresponding mold C , the lower ears y being adapted to cooperate properly with the aligning rib C^1 .

20 In the use of the larger display matrices Z , however, it is necessary to arrest the first elevator at a still higher level in order to present a composed line of such matrices in proper relation to the corresponding mold 25 D . Hence, there is usually provided a second stop member arranged directly alongside the first stop member and mounted to be turned about the same axis into and out of operative position (see Kennedy Patent No. 30 1,595,947). In the present instance, this second stop member J (as will be noted by reference to Figs. 1 and 9) is designed to supplement the member H , the two contact 35 portions J^1 , J^2 of the member J being arranged to coincide respectively with the contact portions H^1 , H^2 of the member H when both members occupy their active position. For this reason, the contact portion J^1 40 is made of such thickness as merely to compensate for the difference in thickness between the lip C^1 of the head-letter mold C and the lip D^1 of the display mold D , so as to arrest the first elevator at the highest or 45 third level when the two contact portions are stacked together for conjoint use. The contact portion J^2 , unlike the corresponding portion H^2 , is integral with the stop member J but it is also made relatively thin so that it 50 may be capable of actuating the vise automatic G through the hinged portion H^2 as the arresting pin E^1 of the elevator banks upon the stacked contact portions J^1 and H^1 .

In the operation of the machine, failure 55 on the part of the operator to adjust the stop members H and J properly to correspond with the mold in use might result disastrously because of interferences between the parts during face alignment. For example: If both of the stop members H and J should 60 (instead of being thrown out of the way) be left in active position when the regular mold B is brought into use, the two-letter matrices X would be presented improperly to the mold as indicated in Fig. 11, due to 65 the fact that the first elevator is arrested

at its highest or third level rather than at the lowest or first level as required. As a result, when the mold is advanced for "face alignment", the mold lip B^1 would strike 70 against the lower ears x and most likely cause

damage to the parts. A similar condition, such as is represented in Fig. 12, would arise if both stop members (instead of the stop member H alone) were left in position when a line of head-letter matrices Y is presented 75 to the mold C . If, on the other hand, both of the stop members H and J were left out of active position at a time when a line of head letter matrices Y is presented to the corresponding mold C or a line of display 80 matrices Z is presented to the corresponding mold D , a condition such as is depicted in Figs. 14 and 13 would result, where the mold in advancing for face alignment would strike 85 against the rear wall of the first elevator.

The present invention is intended to overcome the above and other difficulties and contemplates safety means which are adapted to arrest the operation of the machine whenever any of the foregoing or similar conditions 90 arise through the inattention of the operator. Such safety means (as best shown in Figs. 1 and 3) consist of a movable arresting finger K^1 and a co-related arresting shoulder or lug L^1 , both carried by the first elevator E ; and 95 fixed banking blocks B^3 , C^3 and D^3 associated with the molds B , C and D , respectively, and which are arranged to cooperate with the said arresting members in preventing or 100 permitting the descent of the elevator to the required casting level according to the adjusted position of the stop members H and J .

The finger K^1 (see Fig. 1) is formed at its lower end with an arresting portion K^2 and constitutes one arm of an inverted U-shaped 105 rocking bail K , which is pivoted on a cross pin h in a similarly shaped bracket plate L fastened by screws or similar fastening devices L^6 to an intermediate bracket or spacing block L^2 which is in turn fastened by 110 screws or like devices to the elevator E . The other arm K^2 of the rocking bail is provided at its lower end with a cam shoe K^4 by which the bail may be rocked about its pivotal axis. The bail K is arranged astride the elevator 115 between the side members L^3 , L^4 of the bracket plate L so as to position the finger K^1 in a shallow recess e formed in the rear face of the elevator and to position the shoe K^4 over the vise frame F . The shoe K^4 , as may 120 be observed, is spaced from the arm K^3 by an intermediate block K^5 , which has a sliding engagement with an overlying segmental support L^5 secured to the front side member L^3 of the bracket plate L . The rear side member L^4 is countersunk in the recess e of the elevator and carries the aforementioned lug L^1 , which projects downwardly from the lower edge thereof alongside the arresting finger K^1 . A pull spring K^6 , anchored to the 125 130

bracket plate L and connected to the top portion of the bail K, is employed to hold the arresting portion K² of the finger K¹ resiliently against the lug L¹. The arresting portion K² presents a lower contact surface k¹ spaced below the lug L¹ and inclined upwardly from right to left, and an upper surface k² similarly inclined and which normally (and for reasons presently to appear) fits snugly against the lower edge of the lug L¹ (see Figs. 3, 4 and 6).

The banking blocks B³, C³ and D³ are herein shown as being secured to the mold disc A, but it will be understood that, since each one bears a definite relation to the particular mold with which it is associated, they may if desired be fastened directly to the molds or form an integral part thereof. These blocks are located so as to occupy a position directly beneath the arresting finger K¹ and the arresting lug L¹ when the molds by an adjustment of the disc A are brought into action; the block B³ of the regular mold B (see Figs. 4 and 5) being formed with a single inclined banking surface b to cooperate with the arresting finger K¹; the block C³ of the head-letter mold C (see Figs. 6 and 7) being formed with an inclined banking surface c and a straight or horizontal banking surface c¹ to cooperate with the finger K¹ and the lug L¹, respectively; and the block D³ of the display mold D (see Figs. 8 and 9) being formed with a beveled cam surface d¹ and a single banking surface d to cooperate with the lug L¹.

The arrangement of the parts is such that, if the finger K¹ is allowed to maintain its position against the lug L¹ as the first elevator approaches the casting level, it will be caused to act by its engagement with the blocks B³ or C³ of the respective regular and head-letter molds B and C to arrest the elevator in advance of the stop members H and J; whereas, if the finger K¹ is swung away from the lug L¹, the latter will be permitted to bank upon the block C³ or D³, as the case may be, to arrest the elevator at a similar level.

The operation of the rocking bail K and the arresting finger K¹ is controlled by the supplemental stop member J through the cam shoe K⁴, which latter is adapted, as the elevator descends, to engage said stop member when the latter happens to occupy its inactive position, or to stop short of the vise frame when the stop member occupies its active position. In the former event, the shoe K⁴ will be cammed sidewise toward the left (the segment L⁴ serving through the spacing block K⁵ to absorb the shock caused by contact of the shoe with the stop member J), and the bail K rocked in a clockwise direction against the tension of the spring K⁶ to carry the finger K¹ out of the path of the mold banking blocks. In the latter event, the shoe K⁴ will be undisturbed and the arresting finger

allowed to remain in its active position against the lug L¹ so as to engage the banking blocks and arrest the descent of the elevator. The level at which the elevator is to be sustained in its descent is in this way determined by the finger K¹ or the lug L¹, according to the adjusted position of the stop member J and the particular mold in use.

Fig. 4 shows an abnormal condition with the regular mold B in operative position to cooperate with a composed line of matrices X and the stop members H and J adjusted for a display mold D, and it will be seen that the arresting finger K¹ under such adjustment of the stop members maintains its engagement with the lug L¹ so that the inclined contact surface k¹ thereof will bank upon the corresponding inclined surface b of the block B³ as the elevator E approaches the casting level. At such times, the elevator will be arrested by the block B³ before the pins E¹, E² engage the stop member J, and the automatic G is thus allowed to stop the operation of the machine by causing a disengagement of the main driving clutch in the usual way. In this connection, it may be stated that, due to the close underlying relation of the arresting portion of the finger K¹ to the lug L¹, the shock of the engagement, as well as the weight of the elevator, is sustained directly by the bracket plate L instead of being transmitted thereto through the relatively thin arm K¹ of the rocking bail K. Moreover, the inclination of the banking surface b is adapted to lock the finger in its banking position so as to restrain it against accidental displacement.

On the other hand (i. e., if the stop members H and J occupy their inactive position as shown in Fig. 5), the finger K¹ will be swung clear of the block B³ by the engagement of the shoe K⁴ with the stop member J, and the first elevator E will not be arrested until the stop pin E¹ thereof banks upon the vise frame F. The composed line of matrices X will thus be properly presented at the lowermost level to the mold B, the lower ears α of the matrices being brought into engaging relation to the lower aligning rib B² and the upper characters thereof horizontally aligned with the mold slot. The vise automatic G will in such case be depressed by the pin E² and the cycle of operation allowed to proceed.

Since the operation of the rocking bail K is controlled solely by the stop member J, the arresting finger K¹ will also be moved to its inactive position when the stop member H is employed to arrest the elevator at the intermediate level. Such a condition is shown in Fig. 10, the composed line of matrices X being presented to the mold B at the upper casting level with the lower projecting ears α of the matrices properly aligned with the upper aligning rib B¹ and the lower (italic) char-

acters brought into registry with the mold slot.

When the head-letter mold C is in use, either the finger K¹ or the stop shoulder L¹ is adapted by its engagement with the block C³ of said mold to prevent the operation of the vise automatic G, according to the previously adjusted position of the stop members H and J, it being remembered that the elevator must be arrested at the intermediate level or that determined by the stop member H in order to present a composed line of matrices Y to the mold C in the manner required. Hence, if both stop members should occupy their active position (Fig. 6) as for the display mold D, the first elevator will be arrested at the safety level shown, by the engagement of the finger K with the inclined banking surface c of the block C³; or if both stop members should occupy their inactive position, the finger K will be swung clear of the block C³ by the stop member J and allow the stop shoulder L¹ to bank upon the horizontal surface c¹ of the block and thereby arrest the elevator at a safety level. In either case, the pin E² will fail to depress the vise automatic G and hence will arrest the operation of the machine. However, when the stop members are properly adjusted, as in Fig. 7, (i. e. with the stop member J out of position and the stop member H in position), the elevator will be arrested by the stop member H at the proper (intermediate) casting level and effect the depression of the vise automatic G, the finger K¹ being moved out of the way of the block C³ by the stop member J but the lug L¹ being prevented from contacting with the banking surface c¹.

In the case of the display mold D, the lug L¹ serves exclusively by contact with the banking surface d of the block D³ to stop the descent of the elevator before it can release the vise automatic G when the stop member H is in active position and the stop member J in inactive position. Such a condition is shown in Fig. 8, and the effect would obviously be the same if the position of the respective stop members were reversed or if both were thrown to their inactive position. When both stop members are in active position, as they should be (see Fig. 9), the arresting finger K¹ is pushed aside as the elevator approaches the casting level by the beveled surface d¹ of the block D³, but the lug L¹ will not yet have engaged the banking surface d of the block when the elevator comes to rest upon the stacked stop members.

It will now be clear that the safety devices act in all cases to prevent the presentation of a composed line of matrices to the mold in use unless the stop members are adjusted to arrest the first elevator at the proper level required for that mold, whether it be a regular mold, a head-letter mold, or a display mold. As before stated, these different

molds require the arrest of the first elevator at three different levels, and unless the stop members are properly adjusted with reference to the particular mold in use, the operation of the machine will be arrested before casting takes place and before any damage to the parts can occur.

In practice, all three molds will preferably be mounted upon the same disc and selected for independent use by the rotary adjustment of said disc, but it will be understood that the same effect can be had by placing only one mold on the disc at a time and by removing such mold and replacing it with another when desired. When in the appended claims reference is made to a series of molds of different sizes capable of independent selection, this is intended to embrace these or other arrangements for interchanging the molds, so long as the molds when interchanged are capable of cooperating with the safety devices in the required manner. It may also be noted that, while the stop members herein shown are of the pivoted type, they could be made of the sliding or any other type and mounted on the vise frame or otherwise so long as they are adapted to perform their required functions. As to the safety devices, these too could be variously modified without altering their essential functions or mode of operation.

Having thus described my invention, what I claim is:

1. In a typographical casting machine, the combination of a plurality of molds of different sizes and capable of independent selection, a transporter for presenting a composed line of matrices to the selected mold, adjustable means for determining the level at which the composed line is presented to the mold, and safety devices for preventing the presentation of the composed line to the mold when said level-determining means are improperly adjusted with reference to the mold in use, said safety devices including variant banking blocks associated with the respective molds and cooperative arresting portions carried by the transporter.

2. In a typographical casting machine, the combination of a plurality of molds of different sizes and capable of independent selection, a transporter for presenting a composed line of matrices to the selected mold, adjustable means for determining the level at which the composed line is presented to the mold, and safety devices adapted to stop the operation of the machine when said level-determining means are improperly adjusted with reference to the mold in use, said safety devices including variant banking blocks associated with the respective molds and cooperative arresting portions carried by the transporter.

3. In a typographical casting machine, the combination of a plurality of molds of dif-

ferent sizes and capable of independent selection, a transporter for presenting a composed line of matrices to the selected mold, an adjustable stop member for determining the level at which the composed line is presented to the mold, and safety means operable to prevent or permit the casting operation according to the adjusted position of said stop member, said safety means including variant banking blocks associated with the respective molds and cooperative arresting portions carried by the transporter.

4. In a typographical casting machine, the combination of a plurality of molds of different sizes and capable of independent selection, a transporter for presenting a composed line of matrices to the selected mold, an adjustable stop member for determining the level at which the composed line is presented to the mold, and safety means controlled by the stop member and operable to prevent or permit the casting operation according to the adjusted position of said stop member, said safety means including variant banking blocks associated with the respective molds and cooperative arresting portions carried by the transporter.

5. In a typographical casting machine, the combination of a plurality of molds of different sizes and capable of independent selection, a transporter for presenting a composed line of matrices to the selected mold, two adjustable stop members for arresting the transporter at one level or another according to the mold selected, and safety means operable to prevent or permit the presentation of the composed line to the mold in use according to the adjusted position of the stop members, said safety means including variant banking blocks associated with the respective molds and cooperative arresting portions carried by the transporter.

6. In a typographical casting machine, the combination of a plurality of molds of different sizes and capable of independent selection, a vertically movable transporter for presenting a composed line of matrices to the selected mold, two adjustable stop members for arresting the transporter at one or another level according to the mold selected, and safety means adapted to arrest the transporter during its descent in advance of said stop members when they are improperly adjusted with reference to the mold in use, said safety means including variant banking blocks associated with the respective molds and cooperative arresting portions carried by the transporter.

7. In a typographical casting machine, the combination of a plurality of molds of different sizes and capable of independent selection, a vertically movable transporter for presenting a composed line of matrices to the selected mold, two adjustable stop members for arresting the transporter at one or another

level according to the mold selected, and safety means controlled by one of said stop members for stopping the operation of the machine when the stop members are improperly adjusted with reference to the mold in use, said safety means including variant banking blocks associated with the respective molds and cooperative arresting portions carried by the transporter.

8. In a typographical casting machine, the combination of a plurality of molds of different sizes and capable of independent selection, a vertically movable transporter for presenting a composed line of matrices to the selected mold, two adjustable stop members for arresting the transporter at one or another level according to the mold selected, an automatic device controlled by the transporter for stopping the operation of the machine, and safety means adapted to arrest the transporter during its descent in advance of the stop members to arrest the operation of the machine when the stop members are improperly adjusted with reference to the mold in use, said safety means including variant banking blocks associated with the respective molds and cooperative arresting portions carried by the transporter.

9. In a typographical casting machine, the combination of a plurality of molds of different sizes and capable of independent selection, a transporter for presenting composed lines of matrices to the molds, an adjustable stop member for determining the levels at which the composed line is presented to the molds, fixed banking blocks associated with the respective molds, and means carried by the transporter and adapted to engage said blocks when the stop member is improperly adjusted with reference to the mold in use so as to arrest the elevator in advance of said stop member, for the purpose described.

10. In a typographical casting machine, the combination of a plurality of molds of different sizes, a mold carrier adjustable at will to bring a selected mold into use, a vertically movable transporter for presenting a composed line of matrices to the selected mold, two adjustable stop members for arresting the elevator at one or another level according to the mold selected, and safety means for stopping the operation of the machine when the adjustments of the mold carrier and the stop members do not correspond, said safety means including variant banking blocks associated with the respective molds and cooperative arresting portions carried by the transporter.

11. In a typographical casting machine, the combination of a plurality of molds of different sizes and capable of independent selection, a vertically movable transporter for presenting composed lines of matrices to the molds, two adjustable stop members for ar-

resting the transporter at different levels to bring the lines in proper relation to the respective molds, individual banking blocks for the respective molds, and cooperative arresting portions carried by the transporter and adapted to engage said blocks when the stop members are improperly adjusted with reference to the mold in use, for the purposes described.

12. In a typographical casting machine, the combination of a plurality of molds of different sizes and capable of independent selection, a vertically movable transporter for presenting composed lines of matrices to the molds, two adjustable stop members for arresting the transporter at different levels to bring the lines in proper relation to the respective molds, and safety means for stopping the operation of the machine when the stop members are improperly adjusted with reference to the mold in use, said means including fixed banking blocks associated with the respective molds, and an arresting finger carried by the transporter and movable automatically into or out of engaging relation to said blocks.

13. A combination as specified in claim 12, characterized by the fact that the arresting finger therein recited is spring-actuated and controlled by one of the stop members when in inactive position.

14. In a typographical casting machine, the combination of a plurality of interchangeable molds of three different sizes, means for presenting a composed line of matrices in casting position at one of three different levels according to the mold in use, adjustable means for determining the casting level of the composed line, and safety means controlled by the selection of a mold and the adjustment of the level determining means to prevent the presentation of the composed line at a casting level in conflict with that required for the mold in use.

15. In a typographical casting machine, the combination of a plurality of interchangeable molds of three different sizes, means for presenting a composed line of matrices in casting position at one of three different levels according to the mold in use, adjustable means for determining the casting level of the composed line, and safety means controlled by the selection of a mold and the adjustment of the level determining means to arrest the operation of the machine when the level determining means is improperly adjusted with reference to the mold in use.

16. In a typographical casting machine, the combination of a plurality of interchangeable molds of three different sizes, a vertically movable transporter for presenting a composed line of matrices in casting position at one of three different levels, two adjustable stop members for determining the casting level of the transporter, and safety

means controlled by the stop members for arresting the transporter at a non-casting level when said stop members are improperly adjusted with reference to the mold in use.

17. In a typographical casting machine, the combination of a plurality of interchangeable molds of three different sizes, a vertically movable transporter for presenting a composed line of matrices in casting position at one of three different levels, two adjustable stop members for determining the casting level of the transporter, and safety means controlled by the stop members for arresting the operation of the machine when said stop members are improperly adjusted with reference to the mold in use.

In testimony whereof, this specification has been duly signed by

ANTHONY J. STOUGES.
